PALLET FEEDER MECHANISM FOR
CONCRETE BLOCK MACHINES

Howard D. Corwin, Jackson, Mich., assignor to
The Lith-I-Bar Company, Holland, Mich., a
corporation of Michigan

Original application September 16, 1948, Serial
No. 49,618. Divided and this application Octo-
ber 5, 1950, Serial No. 188,514

2 Claims. (Cl. 25—1)

1

The present application is a division of my application Serial No. 49,618, filed September 16, 1948, and relates to machines for molding building blocks from cement-like material and of the kind which comprises a molding box adapted to be filled with the cement or like moldable mix and the bottom of which box is constituted by a board (usually of metal) upon which the blocks are molded and carried away from the molding station, the machine also embodying a ram structure, operable to pack the material in the molding box, a hopper or equivalent device for feeding the material to the box and mechanism for feeding the boards through the machine. By the expression "cement" it is intended to cover all types of moldable material employed in the manufacture of building blocks, including, in particular, the well known cinder and concrete blocks.

It is an object of this invention to provide in a cement block making machine, which is compact and of relatively small size and with which it is possible to mold blocks at an extremely high rate of speed, a novel board or pallet feeding arrangement.

Other objects and advantages of the invention will be clear from a consideration of the following detailed description of one practical embodiment of the invention with reference to the accompanying drawings, in which,

Fig. I is a side elevational view of a block building machine constructed according to my invention,

Fig. II is an end elevational view of Fig. I looking on the right hand end thereof,

Fig. III is a plan view of Fig. I taken at the level of the work table, with certain parts removed for clarity of presentation, and drawn to a larger scale,

Fig. IV is a transverse section on the line IV—IV of Fig. III,

Fig. V is an enlarged view in section along the line V—V of Fig. III, and showing the construction of the boardways,

Fig. VI is a schematic diagram of the combined fluid pressure and electrical circuit provided to effect and control the operating cycle of my improved block making machine,

Fig. VII is a transverse section on the line VII—VII of Fig. I,

Fig. VIII is a plan view of the moldbox, and

Fig. IX is a plan view along the top of the mix charge slide, with certain parts not shown, and other broken away for clarification.

In Figs. I and II, I have shown my block molding machine, indicated generally at 10, support-

2

ed on a floor 12 by means of a base 14 having upstanding side plates or flanges 16 forming a roundly rectangular well. Positioned at the four corners of this well are the vertical columns 18, 5 20, 22 and 24, which also extend at their upper ends into a vertical well formed by the upper side plates 26 and the top plate 27. This open box-like structure is further strengthened by the addition of a pair of intermediate transverse plates 28 and 10 30 which are attached to the columns 18 and 24, and the columns 20 and 22, respectively, to strengthen the structure, and to support the work table.

Situated within the space defined by the vertical columns 18, 20, 22 and 24 is a vertically movable cage structure, which will be called the "moldbox cage" and is indicated generally at 32. The moldbox cage 32 comprises a horizontal platform 34, a number of upright frame members 36, and the moldbox 38 supported by the upper ends of the uprights 36.

The moldbox 38 may be constructed in any known manner but in the example illustrated in the drawings a particular construction has been 25 adopted to suit the molding of three blocks, simultaneously, it being appreciated however that the actual number may be varied. These blocks, in the particular example illustrated, are of rectangular shape and are preferably molded (as is usual) with one or more vertically extending cavities by the use of appropriate core members located in the moldbox. It is desired to point out here, however, that the invention is not limited to this or any other particular shape of the 30 blocks, since these may be solid or cored or of various shapes and sizes including, cylindrical, conical and pyramidal shapes.

The particular moldbox shown in the drawings (Figs. I and II) is of rectangular shape and is open at both top and bottom. In operation its bottom is constituted by one of the workboards, to be described later and indicated at 120. The interior of the moldbox is subdivided by transversely extending partition walls 38a to form three 45 compartments 38b in each of which there is located one or more vertical core members 38c, the number and shape of which will depend upon the number and shape of cavities desired to be present in the molded blocks. These core members 38c are suspended from transversely extending stretcher bars 38d which are themselves supported upon flanges 38e formed along the upper edges of the moldbox side walls.

Fastened to the upright frame members 36 for 50 rolling engagement with the sides of the vertical

columns 18, 20, 22 and 24 are a number of anti-friction rollers or guide wheels 40 which guide the moldbox cage 32 in its vertical movement within the space defined by the four columns.

The moldbox cage 32 is supported to move within the main framework of the machine by the engagement of the piston rod 42 with the base 34, and by the movement imparted to the rod 42 from a fluid-pressure cylinder 44, which is preferably mounted partially in the floor 12, and within the well defined by the side plates 16.

It may be mentioned here that I propose to employ hydraulic cylinders and associated pistons and pipe lines for effecting the required movements of the various operational parts of my machine but at the same time I do not wish to preclude the possibility of employing a pneumatic pressure operating medium.

The piston rod 42 extends through a bellows 46, which protects the rod from the molding material. I have also shown in Fig. I a broken-off hydraulic line 48, which leads to the rod end of the cylinder 44, and a similar line 50 which leads to the head end of the cylinder 44. From this structure, it should be apparent that the introduction of hydraulic fluid through the line 50 into the head end of the cylinder 44 will cause the piston rod 42, and, therefore, the moldbox cage 32 and the moldbox 38, to move vertically, the same being controlled and guided by the guide wheels 40. The releasing of pressure from the line 50 and the introduction of hydraulic pressure fluid to the line 48 will cause the moldbox cage 32 to move in a downward direction, within the limits of the structure.

Attached to the upper plate 27 is a further plate member 52, from which is suspended the ram operating cylinder 54, with a hydraulic line 56 entering the head end of this cylinder and another hydraulic line 58 entering the rod end of the cylinder. The piston rod 60 supports and controls the movement of the ram cage 62, which employs a number of guide wheels 64 for rolling engagement with the sides of the columns 18, 20, 22 and 24, and supports the ram structure, indicated generally at 66, as well as vibrators 68. These vibrators are shown only generally in Figs. I and VI and their purpose is to shake the ram structure and thereby assist in the packing of the molding material into the moldbox. The ram structure comprises a series of plates 66a, there being two provided for operation in association with each moldbox compartment 38b, positioned to clear the partition walls 38a and the stretcher bars 38d and having their opposed inside faces recessed, as indicated at 66b to clear the mold cores 38c.

From the above it will be appreciated that, upon the introduction of hydraulic fluid through the line 56 to the head end of the cylinder 54, the ram cage 62 will move downwardly and thereby force the lower ends of the ram plates 66a against the molding material previously deposited in the moldbox compartments 38b in a manner yet to be described. Upon the release of hydraulic pressure from the line 56 and the supplying of fluid through the line 58 to the rod end of the cylinder 54, the ram cage 62 and its associated ram structures 66 will be lifted from engagement with the material within the moldbox 38 and will be returned to the position shown in Fig. I.

It must be appreciated that the operations of the ram cage 62 and the moldbox cage 32 are entirely independent.

To provide an automatic transfer of the correct

amount of cement or other moldable mixture from the hopper 70 to the moldbox 38, I have devised a mix charge slide, indicated generally at 72, and mounted such slide on a pair of arms 74 which extend rearwardly from the machine, as seen in Fig. II, and which arms are supported in any suitable manner, such as by the bracket plate 76. The arms 74 support a table 78 between them, which table extends up to the upper edge of that side wall of the moldbox from which this table extends and serves to support the slide 72 for reciprocatory sliding movement thereon. The slide 72 is of elongated rectangular form, as seen particularly in Fig. IX, and comprises a rear portion constituted by a plate 82 and a front portion, in the form of a bottomless rectangular chamber 81 corresponding approximately in shape and size to the moldbox 38, this chamber 81 being also open at the top. The construction and arrangement is such that in one extreme position, as shown in Figs. II and IX, this chamber is positioned immediately over the top of the moldbox 32 and the plate 82 closes the bottom of the hopper 70, whereas in its other extreme position the chamber 81 is positioned immediately opposite the bottom of the hopper and is accordingly then filled from the hopper. It will be readily understood that this particular construction amounts to an automatic metering and valve control of the mix charge. Attached to the rearwardly extending ear 84 is the pivoted arm 88 which in turn is attached to another pivoted arm 90. Mounted between the pivoted arm 88 and the frame of the machine is the mix charge cylinder 92 having its head end mounted on the machine 10, and having its rod 94 pivotally mounted on the arm 88. It will be understood that the introduction of hydraulic fluid through the line 96 into the head end of the cylinder 92 will result in a rearward movement of the mix charge slide 72, back to the center position 88. From that position, introduction of hydraulic fluid under pressure through the line 100 into the rod end of the cylinder 92 will result in a movement of the mix charge slide 72 forwardly to the center position 88. With the mix charge slide 72 in the position shown in Figs. II and IX, the mix is dumped from the bottomless mix receptacle 89 into the moldbox 38. To facilitate this dumping operation and to make sure that the entire contents of the receptacle are dumped into the moldbox 38, I have provided the receptacle with a series of vibrator blades 102 carrying masses 103 and arranged for the same to be actuated by a vibrator 104 secured upon the receptacle 89. When the vibrator 104 is operating the entire mix charge slide 72 will vibrate slightly, and the blades 102 will vibrate quite actively.

As is usual, in the art of block making I employ wooden pallets to constitute work boards upon which the cement blocks are formed and supported. In this connection, it is necessary to have, first, a station to which the work boards with the blocks thereon are moved, and from which last mentioned station the blocks may be moved upon their boards for curing and storage. To provide for these three stations, I have constructed a work table, indicated generally at 106, in the form of an elongated rectangular frame which extends outwardly on both sides of the machine 10. This work table frame is made up of a pair of longitudinal rails comprised one by an adjacent pair of rails 108 and 110 and the other by an adjacent pair of rails 112 and 114. These rails are supported upon transverse side plates 28

and 30 themselves secured to opposite sides of the machine columns. Of these pairs of rails, those at 108 and 114 extend the full length of the work table frame 106, while those at 110 and 112 extend from the work board storage station and terminate adjacent the plate 28. All these rails are preferably formed with their top edges bevelled, chamfered, or somewhat rounded in order that any of the cement mix which happens to fall loosely as waste around the machine will not adhere to or pile up on the rails.

At the first station on the work table 106, I have provided a hopper comprising a U-shaped vertical rear section 116 and a U-shaped vertical front section 118. These sections 116 and 118 extend transversely across the boardways constituted by the rail structures above described and define a rectangular hopper 115 into which the work boards 120 may be stacked in orderly arrangement. The section 116 is provided with a transversely extending lower aperture 122, the purpose of which will appear later. Likewise the section 118 is provided with a transversely extending lower aperture 124 through which the lowermost board of the stack may be moved along the work table 106 from the hopper 115 to the second station, where this board forms the bottom of the moldbox 38.

To provide for the guiding of the work boards 120 as they are moved from the hopper 115 to beneath the moldbox 38 I have provided a pair of vertically positioned outer walls 126 (Fig. IV) which may be fastened to the rest of the structure by any suitable means such as the angle members 128. The guide walls 126 extend from the rear wall 116 of the hopper to a point substantially adjacent the vertical columns 18 and 24.

Referring particularly to Figs. III, IV and V, an understanding may be obtained of the rail structure which I employ to move the work boards from the hopper 115 to beneath the moldbox 38, and then to the third or removal station, this being located upon the left-hand part of the table 106 as seen in Fig. III. In this connection it has already been mentioned that the rail structure forms the longitudinals 108, 110 and 112, 114 of the elongated rectangular frame, constituting the work table 106.

Each such longitudinal is of composite construction, as shown in Figs. IV and V, and is formed by a pair of main rails 132 (the innermost of which is shorter than the other and corresponds to the aforesaid longitudinal 110 or 112) and by separate top rails 134 secured upon the upper edges of their respective main rails, as by screws 130. These rails are arranged in parallel spaced relationship to form an interior longitudinal channel 140 between them which is open at both top and bottom and is recessed upon its opposite and closed side walls to form slideways 141 for a pair of longitudinally extending slide plates 142 held together, as by rivets 146, with the intervention of spacer blocks 144, disposed at longitudinally spaced intervals along the opposed slide plates 142. The upper and lower edges of these plates are overlapped by the overhanging portions 132a and 134a of the main rails and of their upper and separate rails 134, whereby these surfaces are protected from the molding material which tends to fall through the openings between the rails and the interposed spacer blocks and hooks 154 and 158, now to be described. These are provided between the opposed pairs of slide plates 142 for movement with the latter and the one pair of hooks is longitudi-

nally spaced from the outer pair a distance corresponding to that required to permit the simultaneous pulling action above mentioned. It may be stated here, however, that the one pair of hooks 158 operate to pull the work board at the bottom of the moldbox 38 whereas the other pair of hooks 154 operate to pull the board at the bottom of the hopper 115, the transverse slot 122 at the remote end of the hopper serving to permit the necessary ingress of these hooks for this purpose, as will be understood.

The hooks are pivotally mounted upon the slide plates 142, at one end, as indicated at 154a and 158a and at their opposite and hook ends have cam surfaces 156. By a suitable spring or weight mounting of the hooks provision may be made whereby their hook ends normally project above the work table rails in position to engage their respective work boards for the desired pulling engagement therewith but are capable of being automatically depressed, by the camming action produced upon these cam surfaces 156 when the slides 142 are moved back after the completion of a board pulling operation.

Secured to the ends of the slide members 142, nearest the vertical machine columns 18 and 24, and connecting them together for co-ordinated movement, is a bar 148 (Fig. III) which is further connected with a piston rod 150 of a work board transfer cylinder 152.

It will be understood that the introduction of pressure fluid through the pipe line 160 to the head end of this cylinder 152 will impart movement to the bar 148 and hence to the slide members 142 in one direction, to cause the hooks to engage their respective boards and pull them along the work table, as above mentioned. On the other hand, the introduction of hydraulic fluid under pressure through the line 162 to the rod end of the cylinder 152 will return the slides 142 to their original position, as shown in Fig. III. A cover plate 164 extends from the rod end of the cylinder 152 to the termination of the rails 108 and 114 at the connecting cross bar 166 (Fig. III), and functions to prevent any of the floating molding material from contacting the piston rod 150. The rails 108 and 114 are formed with indentations 168 to permit the use of mechanical lift trucks for the removal from the work table 106 of a work board loaded with newly molded blocks, as seen at the left of Fig. I.

It will be appreciated, from a consideration of the description thus far, that I have, at every opportunity, attempted to safeguard the operating parts of the machine from the loose particles of the molding material, which tend to fall about the machine during the molding operation. I have provided that all machine surfaces which require to have operational engagement with other machine surfaces are either covered to protect them from such material, or are so shaped (as by making the upper surfaces of the spacer blocks 144 of shed formation) as to dislodge any material which tends to collect thereon. This will materially lessen the operating cost of the machine, since it will be relatively easy to keep clean.

Operation

Referring now to Fig. VI, the schematic diagram showing the hydraulic or fluid pressure system and the electrical control circuit for effecting and controlling the automatic operation of my block molding machine 10, it will at once be appreciated that such a control system will work best if it is isolated completely from any

of the dirt normally associated with the making of "cement" blocks, and I therefore recommend that as much of the control panel and mechanism, including the hydraulic tank and electric motor and pump, should be placed in a separate room from the one in which the block making machine is operated and that electric wires and pipes should be provided to make the required connections between the two rooms.

I have devised this particular pressure system and control circuit in order that the operation of the block building machine shall be completely automatic, aside from the filling of the hopper 70, the placing of the work boards 120 in their hopper 115, and the removing of the completed blocks from the machine.

I have also made use of standard "Vickers" hydraulic pumps and valve units and connected the same in a hydraulic circuit, as will appear from the following description and will be clear to those skilled in the art of hydraulics, in particular.

Briefly, the hydraulic circuit comprises a "Vickers" double pump and combination valve unit 174, actuated by a separate electric motor 172, a "breather" tank 170 filled with the hydraulic medium, a relief valve 176, four "Vickers" double solenoid controlled pilot operated four-way valves, indicated generally at A, a de-presurizing and pressure control valve 178 and three "Vickers" pilot operated check valves, indicated generally at B, B and C, the latter being connected for use as a sequence valve.

As these pump and valve units are well known standard equipment in the hydraulic field it is considered unnecessary to illustrate or describe the same in detail and that the following sequential and functional operation thereof to suit the various movements of the machine components i. e. the work board feed hooks 154 and 158, the mix charge slide 72, the moldbox 38 and the ram structure 66.

At the commencement of a complete operating cycle of the machine these components are situated as follows:

- (1) The hooks 154 and 158 are situated as shown in Fig. I, with the hooks 154 ready to pull a work board 120 forward along the work table 106.
- (2) The mix-charge slide 72 is in a rearward position, as compared with its position in Fig. II, with its charge receiving compartment 81 located at the bottom of the hopper 70.
- (3) The moldbox is in the raised position, in which the ram structure 66 is nested within the moldbox, and
- (4) The ram structure is in the raised position, as shown in Fig. I.

Now let it be assumed that the oil tank 170 is filled, motor 172 has been started, pump 174 is circulating oil back to the tank 170 through the relief valve 176, this valve being vented through the now de-energized solenoid valve 178 to return the entire pump output back into the tank 170. To commence an operating cycle, the start button 180 is pressed, which closes the contractor 182 and energizes the solenoid valve 178, sending hydraulic fluid under pressure to the machine through the valve 184 to the head end of the work board transfer cylinder 152. This causes the bottom work board 120 in the work board hopper 115 to be pushed along the work table 106 to beneath the moldbox 38, to close the latter.

The limit switch 186 is also closed, which in turn energizes the time switch 188, and energizes the contactor 190 which momentarily causes the valve 192 to shift, allowing fluid to flow to the rod end of the moldbox lift cylinder 44 to bring the moldbox 38 down onto the work board 120. As pressure is driven into the cylinder 44 the check valve 194 is held open allowing fluid from the head end of the cylinder 44 to return to the tank 170. This check valve 194 positively holds the moldbox 38 in the up position when it is supposed to be up. As the moldbox 38 descends, it closes the limit switch 196, which energizes the time switch 198, which in turn energizes the contactor 200, momentarily causing the valve 202 to shift and allow fluid to flow to the rod end of the mix transfer cylinder 92 which moves the material containing slide compartment 81 from the hopper 70 to above the moldbox 38. As the mix charge slide 72 stops it closes the limit switch 204 which energizes the time switch 206, in turn energizing the contactor 208 and starting the vibrator 104, which vibrates the charge box 80 and the blade members 102 to clear the cement mix out of the compartment 81. The time of vibration may be set by adjustment of the time switch 206. As soon as this time has elapsed, the time switch 206 reverses, which energizes the contactor 210 to cause the valve 212 to shift and allow the pressure fluid to flow to the head end of the mix transfer cylinder 92, thereby returning the mix slide 72 to the starting point, where it is automatically reloaded from the hopper 70. At this point the limit switch 214 is closed, energizing the time switch 216, which in turn energizes the contactors 218 and 220 to momentarily cause valve 222 to shift and allow the fluid to operate against the plug 224 in the valve 222; this also causes the valve 226 to shift and allow fluid to flow through the sequence valve 228 to the head end of the ram cylinder 54, thereby lowering the ram 66 onto the surface of the material in the moldbox. As pressure is built up in the cylinder 54, the check valve 230 is opened, to allow fluid from the rod end of the cylinder 54 to return to the tank 170. This check valve 230 positively holds the ram 66 in the up position during the time it is supposed to be up and performs similarly to the check valve 194. As the ram 66 reaches the bottom, the pressure breaks through the sequence valve 228 and flows to the rod end of the board transfer cylinder 152 which returns the board transfer slide and the operating members 142 to their starting point. As the ram 66 reaches the limit of its descending motion it also closes the limit switch 232, which energizes the time switch 234, which in turn energizes the contactor 236 to operate the vibrator 68 on the ram for an adjustable and predetermined time, after which the time switch 234 reverses, shutting off the vibrator 68 and energizing the contactor 238. The latter, in turn, energizes the valve 240, allowing fluid to flow without restriction through the valve 194 to the head end of the moldbox lift cylinder 44, causing the moldbox, together with its frame structure 36, to be lifted bodily against the still covered ram structure 66, whereby the latter moves through the moldbox and, by continued pressure on top of the molded blocks strips the latter from the mold and leaves them supported upon the work board. As the moldbox 38 reaches its top-most position, it closes the limit switch 242 which closes the contactor 244 which in turn energizes the valve 246 to allow the fluid to flow without

restriction through the valve 230 to the rod end of the ram cylinder 54, thereby causing the ram structure 66 to be lifted to its raised position. As the ram 66 reaches its top limit it closes the limit switch 248, thereby closing the contactor 250, which in turn reenergizes the valve 184, so that the machine is re-set for a fresh operating cycle.

It will be appreciated by those skilled in the art, that a failure of the electrical current in this system will not affect the timing of the operation upon the restoration of electric service. The equipment has also been designed to operate at a very high rate of speed, in that all of the timers can be set at between one and one and a half seconds, with the exception of the time switch 234, which controls the ram pressure time, and the time switch 206, which controls the mix dump time, which may be set as desired to accomplish the required operation.

In order to stop the automatic cycle, the stop switch 252 is pressed which opens the contactor 182 which in turn de-energizes the solenoid valve 178 and allows the fluid to be pumped through the relief valve 176 back into the tank 170.

Having thus described my invention, what I claim as new and desire to protect by Letters Patent is:

1. In a machine for molding building blocks with the use of a moldbox having an open bottom adapted to be closed by a separate block supporting workboard, a worktable for supporting said workboard, said worktable including a plurality of composite longitudinal rail structures upon which the board is moved to the moldbox bottom closing position, each rail structure being formed of a pair of parallel rails assembled in juxtaposition to provide an interior channel open at the top and bottom and having recessed interior side walls, board propelling operative members confined within each said recessed side wall and adapted for longitudinal

movement therein while protected from the effect of the molding material tending to fall through the top opening in the rail structure, and spacer means between said operative members, said spacer means being located in the open channel portion.

2. In a machine for molding building blocks onto separate workboards through a moldbox having both its top and bottom open, the provision of a worktable adapted to support and move said workboards, said worktable comprising a plurality of composite longitudinal rails, each of said rails including a pair of longitudinally extending parallel vertical side walls mounted on said machine and enclosing a channel which is open at both the top and bottom, said side walls being formed with parallel internal channels opening to said first channel, a longitudinal strip member mounted for reciprocatory sliding movement in each of said second channels, means mounted on said strip members and positioned in said first channel to maintain each pair of said strip members in spaced relationship and in position in said second channel, means mounted on said strip members and adapted to move said workboards along said worktable, means connecting said strip members together for unitary movement, and power means associated with said connecting means and adapted to impart reciprocatory movement to said strip members.

HOWARD D. CORWIN.
